THERMOSTATIC ELECTRIC HEATING
APPLIANCE

Ludwig Reichold, Winsted, Conn., assignor to The
Winsted Hardware Manufacturing Company,
Winsted, Conn., a corporation of Connecticut

Application February 11, 1935, Serial No. 5,980

13 Claims. (Cl. 219—25)

This invention relates to automatic temperature-controlled electrically-heated appliances, and more particularly to an automatic flat-iron in which the "on" and "off" switch for the heating element is directly operated by the expansion and contraction of the sole plate.

One object of this invention is to provide a flat-iron of the above nature in which the temperature is maintained within very close limits, thus permitting a reduction of power input over that commonly used.

A further object is to provide a flat-iron of the above nature in which the switch for opening and closing the circuit through the heating element is actuated by the toggle action of a pair of cooperating bars, the ends of which are seated upon a pair of spaced thrust members fastened to the sole plate.

A further object is to provide a device of the above nature which will be simple in construction, inexpensive to manufacture, easy to assemble and manipulate, compact, ornamental in appearance, and very efficient and durable in use.

With these and other objects in view, there has been illustrated on the accompanying drawing, one form in which the invention may be conveniently embodied in practice.

In the drawing:

Fig. 1 represents a longitudinal sectional view through a flat-iron embodying the invention.

Fig. 2 is a plan view of the same with the top shell and associated parts removed.

Fig. 3 is a diagrammatic view of the thermostatic controlling mechanism, and the electrical circuit automatically controlled thereby.

Many attempts have been made in the past to provide an electric heating appliance, such as a flat-iron, which would remain at a constant even temperature, even when the heat demanded therefrom was variable. In most irons it was necessary to employ a heating element having a capacity exceeding the maximum heat consumption of the iron in order to shorten the delay or "lag" in the action of the thermostat which was generally of the bimetallic strip type. Such flat-irons are relatively sluggish in action due to the relatively large temperature drop between the sole plate and the bimetallic unit or other heat controlling member. This temperature drop is due to the fact that the thermostat receives its heat indirectly by conduction, radiation or convection from the sole plate; and in fact, the thermostat was sometimes insulated from the sole plate by mica or other materials. The lag in

such irons was still further increased by reason of the fact that the metals employed in the bimetallic strips were of relatively low heat conductivity, and hence, were slow to respond to temperature changes.

By means of the present invention, the above and other disadvantages have been avoided by so constructing the iron that the sole plate or other heat-applying element forms a part of the thermostatic mechanism.

Referring now to the drawing in which like reference numerals denote corresponding parts throughout the several views, the numeral 10 indicates a metal sole plate, preferably constructed of relatively thin metal so as to allow the heating element to be positioned close to the material being ironed, and to permit the thermostatic control device to expand and contract more rapidly due to temperature changes. The sole plate 10 is located under a filler block 11 of relatively thick metal, and is secured thereto by a pair of upstanding bolts 12 and 13 having frusto-conical heads which, as shown in Fig. 1, are adapted to be secured in a pair of circular recesses 14 provided in the upper surface of the sole plate 10. The bolts 12 and 13 extend upwardly through an elongated slot 15 in the filler block 11.

The forward bolt 12 is tightly clamped upon the filler block 11 by means of a nut 16 engaging the base section of an angle bracket 21 seated in a depression 18 formed on the top of said filler block. The rear end of the filler block 11 is adapted to support a base plate 19 forming an integral part of a U-shaped prong-carrying shell 20. The base plate 19 overlaps the rear end of the longitudinal slot 15, and is tightly held down upon the filler block 11 by means of a binding nut 22 screwed on the bolt 13.

A flat mica-enclosed heating element 23 of the conventional U-shaped form is located in direct contact with the upper surface of the sole plate 10, said heating element being separated from the superimposed filler block 11 by a sheet of asbestos material 24 having the same shape as said heating element 23. The terminals of the heating element 23 are connected in an electric circuit, including a pair of upstanding rearwardly inclined prongs 25 and a temperature responsive switch to be described later. The prongs 25 are rigidly connected to the U-shaped shell 20, being insulated therefrom in the usual manner.

The upper part of the sole plate 10 and associated parts carried thereby are completely enclosed by means of the usual thin metal cover shell 26. Provision is also made of a U-shaped

handle bracket 27 having its lower front end rigidly supported upon the cover shell 26. The bracket 27 supports a heat insulating tubular handle 28 held in place by means of an elongated bolt and nut, not shown, attached to the upper end of said bracket. The handle bracket 27 has a rearwardly-opening oval-shaped socket 29 surrounding the contact prongs 25. The cover shell 26 and its attached handle bracket 27 is held in position on the top surface of the sole plate 10 by means of a socket nut 30 screwed upon the upper end of the rear bolt 13.

Thermostatic mechanism

15 The temperature-responsive switch operating mechanism includes three members:

A. The portion of the sole plate 10 lying between the bolts 12 and 13, said portion being conveniently indicated by the letter "P";

20 B. A slightly inclined longitudinal thrust bar 31 provided with oppositely beveled extremities 32 and 33,—the left-hand extremity 32, as shown in Fig. 3, being adapted to pivotally engage in a V-shaped notch 34 provided on the rear side of the head of the bolt 12; and

C. An inclined third class lever 36 having a reentrant angle bend 35 formed in the intermediate section thereof for receiving the right-hand beveled extremity 33.

30 The lever 36 has a short lower end 37 provided with a beveled extremity 38 which is fulcrumed in a notch 39 in the head of the bolt 13. From this construction it will be noted that the thrust bar 31 and the short end 37 of the lever 36 define the two short sides of a triangle in which the plate "P" constitutes the hypotenuse.

The thrust bar 31 and the lever 36 are preferably constructed of a metal or metals having a coefficient of expansion considerably lower than 40 the material of the sole plate 10. Consequently, when the plate "P" expands due to heat applied thereto from the heating element 23, the bar 31 and the cooperating lever 36 will swing downwardly under the influence of a downwardly 45 pressing leaf-spring 40 having its opposite end rigidly anchored to the bolt 13 between a pair of opposed nuts 41. The upper portion 42 of the lever 36 extends a considerable distance beyond the bend 35 thereof, so that the expansion of the sole plate section "P" will be greatly magnified thereby. The portion 42 is bent at a slight angle and is normally in a substantially horizontal position and out of engagement with a thrust button 43 made of insulating material 50 and carried on the lower leg 44 of a J-shaped movable contact bar 44a. The upper leg 44b of the contact bar 44a is considerably longer than the lower leg 44 thereof, and is secured, as by riveting, to the free end of a flat elongated leaf-spring 44c. The other end of the leaf-spring 44c is made rigid to an angle support 45 which is electrically connected with the heating element 23. The upper leg 44b of the contact bar 44a carries a movable contact button 46, preferably of silver, adapted to normally engage with a similar contact button 47 riveted or otherwise secured to the free end of an adjustable resilient conductor strip 48. The rear end 48a of the conductor strip 48 is bent laterally and 60 is anchored to one of the contactor prongs 25, as by means of nuts 49.

In order to simultaneously and manually adjust the vertical position of the upper button 47 and lower button 46 which are normally in contact with each other, provision is made of a

thrust spool 50 of porcelain or analogous insulating material, which is adapted to freely pass through alined slots provided in the conductor strip 48 and the upper leg 44b of the J-shaped contact bar 44a, respectively. The upper end 5 of the thrust spool 50 is provided with an enlarged head 51 which is adapted to engage the top surface of the conductor strip 48. An adjusting screw 52 is located in axial alinement with the bushing 50 and engages the top of the enlarged head 51. The adjusting screw 52 is screwed into the upper horizontal section of the angle bracket 21 and has at its upper end a reduced section 52a which is adapted to pass through a tubular eyelet 53 located in the cover 10 shell 26 and handle bracket 27. A manually-operated temperature-regulating arm 54 is secured to the top of said reduced section 52a.

Operation

In operation, the flat-iron will first be connected to a source of electric current by means of the prongs 25 and a plug, not shown. The switch being normally closed, the heating unit 23 will be immediately energized and will heat 25 the sole plate 10. As the plate 10 expands due to the rise in temperature, the distance between the bolts 12 and 13 will gradually increase, causing the thrust bar 31 and lever 36 to swing downwardly, and after a predetermined temperature 30 is reached, causing the arm 42 to engage the insulating button 43 and cause the J-shaped bar 44a to separate the contact buttons 46 and 47 and open the circuit. When the plate cools, the bar 31 and lever 36 will be caused to swing 35 upwardly by a toggle action, causing the circuit to be again closed. The operating temperature of the flat-iron may be readily fixed by manually rotating the screw 52 to the desired point, thereby varying the distance between the buttons 46 40 and 47.

While the thrust bar 31 and lever 36 have been herein described as made of metal, it will be understood that either or both of these parts may be made of any suitable material, such as 45 quartz, quartz glass, carbon, or lava within the spirit and scope of this invention.

While there has been disclosed in this specification one form in which the invention may be embodied, it is to be understood that this form is 50 shown for the purpose of illustration only, and that the invention is not to be limited to the specific disclosure but may be modified and embodied in various other forms without departing from its spirit. In short, the invention includes 55 all the modifications and embodiments coming within the scope of the following claims.

Having thus fully described the invention, what is claimed as new, and for which it is desired to secure Letters Patent, is:

1. In an electrically heated flat-iron, a sole plate, a heating element for supplying heat to said sole plate, a circuit including a switch for supplying current to said element, a pair of oppositely inclined bars having their lower ends in 65 pivotal engagement with spaced points on said base, the upper end of one of said bars engaging the other bar, said bars having a coefficient of expansion different from that of said sole plate whereby said bars will be lowered and raised with 70 respect to said plate coincident with the expansion and contraction thereof, and means responsive to the movement of said bars for opening and closing said switch.
2. In an electrically heated flat-iron, a sole 75

plate, a heating element for supplying heat to said sole plate, a circuit including a switch for supplying current to said element, a pair of oppositely inclined bars having their lower ends in pivotal engagement with spaced points on said base, the upper end of one of said bars engaging an intermediate section of the other bar, said bars having a coefficient of expansion different from that of said sole plate whereby said bars will be lowered and raised with respect to said plate coincident with the expansion and contraction thereof, and means responsive to the movement of said bars for opening and closing said switch.

3. In an electrically heated flat-iron, a sole plate, a heating element for supplying heat to said sole plate, a circuit including a switch for supplying current to said element, a pair of oppositely inclined bars having their lower ends in pivotal engagement with spaced points on said plate, the upper end of one of said bars engaging the other bar, said bars having a coefficient of expansion different from that of said sole plate whereby said bars will be lowered and raised with respect to said plate coincident with the expansion and contraction thereof, and means responsive to the movement of said upper bar for opening and closing said switch.

4. In an automatic electric heating appliance, a heat applying member, an electric heating element for supplying heat to said member, a circuit including a switch and said heating element, an inclined bar and an oppositely inclined lever engaging said member at spaced points, said bar being fulcrumed between the ends of said lever forming a toggle, said bar and lever being constructed of a material having a lower coefficient of expansion than that of said heat applying member, and means responsive to the movement of the upper end of said lever for opening and closing said circuit.

5. In an automatic electric heating appliance, a heat applying member, an electric heating element for supplying heat to said member, a circuit including a switch and said heating element, an inclined bar and an oppositely inclined spring-pressed lever engaging said member at spaced points, said bar being fulcrumed between the ends of said lever forming a toggle, said bar and lever being constructed of a material having a lower coefficient of expansion than that of said heat applying member, and means responsive to the movement of the upper end of said lever for opening and closing said circuit.

6. In an automatic electric heating appliance, a heat applying member, an electric heating element for supplying heat to said member, a circuit including a switch and said heating element, an inclined bar and an oppositely inclined lever having an intermediate shoulder engaging said member at spaced points, said bar being fulcrumed in said shoulder forming a toggle, said bar and lever being constructed of a material having a lower coefficient of expansion than that of said heat applying member, and means responsive to the movement of the upper end of said lever for opening and closing said circuit.

7. In an automatic electric heating appliance, a wall member which is free to expand and contract, an electric heating element, a circuit including a switch and said heating element and having connections to a source of current, an inclined bar and an oppositely inclined lever engaging said wall member at spaced points, the other end of said bar being fulcrumed between

the ends of said lever, said bar and lever being constructed of a material having a lower coefficient of expansion than that of said wall member, and means responsive to the movement of the free end of said lever for opening and closing said circuit.

8. In an automatic electric heating appliance, a wall member which is free to expand and contract, an electric heating element, a circuit including a switch and said heating element and having connections to a source of current, an inclined bar and an oppositely inclined lever engaging said wall member at spaced points, the other end of said bar being fulcrumed between the ends of said lever, said bar and lever being constructed of a material having a lower coefficient of expansion than that of said wall member, and a switch responsive to the movement of the free end of said lever for opening and closing said circuit.

9. In an electrically heated appliance, a heating plate, electrical means for heating said plate, an electric circuit for supplying current to said means, a switch for controlling said circuit, a pair of cooperating upwardly-extending switch-actuating toggle bars having their lower ends engaging a pair of spaced points on said plate, one or both of said toggle bars having a coefficient of expansion different from that of said plate, the unequal expansion and contraction of said plate and bars causing said toggle bars to open and close said switch.

10. In an electrically heated flat-iron, a sole plate, an electrical heating element for supplying heat to said sole plate, a switch located above said sole plate for controlling a circuit for supplying current to said element, a pair of spaced notched heads embedded in the upper surface of said sole plate, a pair of upwardly-extending oppositely-inclined switch-actuating bars having their lower ends seated in pivotal engagement with the notches of said heads, one of said bars engaging the other bar and having a coefficient of expansion different from that of said sole plate whereby said bars will be moved with respect to said plate by the expansion and contraction thereof, and means responsive to the movement of said bars for opening and closing said switch.

11. In an electrically heated flat-iron, a sole plate, a heating element for supplying heat to said sole plate, a switch having a vertically movable contact located above said sole plate for controlling the supply of current to said element, a pair of oppositely inclined switch-actuating up-standing bars beneath said switch and having their lower ends in pivotal engagement with spaced points on said plate, the upper end of one of said bars engaging an intermediate section of the other bar, said first mentioned bar having a coefficient of expansion different from that of said sole plate whereby said bars will be lowered and raised with respect to said plate coincident with the expansion and contraction thereof, the up and down movement of said bars causing the opening and closing of said switch.

12. In an automatic electric heating appliance, a wall member which is free to expand and contract, an electric heating element, a switch for controlling a circuit including said heating element and having connections to a source of current, an upwardly extending inclined bar and an oppositely inclined switch-actuating lever engaging said wall member at spaced points, the upper end of said bar being fulcrumed between the ends of said lever, said bar being constructed of a ma-

terial having a lower coefficient of expansion than that of said wall member, the movement of the free end of said lever serving to open and close said switch.

5 13. In an automatic electric heating appliance, a wall member which is free to expand and contract, an electric heating element therefor, a circuit including a switch and said heating element and having connections to a source of current, an inclined bar and an oppositely inclined

lever engaging said wall member at spaced points, the other end of said bar being fulcrumed between the ends of said lever, said bar being constructed of a material having a lower coefficient of expansion than that of said wall member, and 5 a switch responsive to the movement of the free end of said lever for opening and closing said circuit, the plane formed by said bar and lever being substantially at right-angles to said plate.

LUDWIG REICHOLD 10
